UNITED STATES PATENT OFFICE.

BENJAMIN FRANKLIN PEASE, OF CINCINNATI, OHIO, ASSIGNEE TO THE OHIO TRUSS CO., OF CINCINNATI, OHIO.

ARMREST.

1,376,380.

Specification of Letters Patent. Patented Apr. 26, 1921.

Application filed May 3, 1920. Serial No. 379,913.

To all whom it may concern:

Be it known that I, BENJAMIN FRANKLIN PEASE, a citizen of the United States, residing at Cincinnati, in the county of Hamilton and State of Ohio, have invented a new and useful Armrest, of which the following is a specification.

This invention relates to arm rests particularly designed for use in connection with 10 crutches and the like, one of the objects being to provide an arm rest which can be applied readily to its supporting structure, the said arm rest, whether padded, provided with springs, or of any other construction 15 being attached firmly without the necessity of utilizing a plurality of fastening devices along the side of the crutch top or by using other tedious and expensive means of fastening.

20 A further object is to provide an arm rest which can be easily made, the parts of which are held together securely, and which in no sense detracts from the appearance of the crutch.

25 With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

30 In the accompanying drawings the preferred form of the invention has been shown.

In said drawings—

Figure 1 is a longitudinal section through the top piece of a crutch and through the 40 arm rest secured thereon.

Fig. 2 is a section on line 2—2, Fig. 1.

Fig. 3 is a bottom plan view of the arm rest detached.

Fig. 4 is an end elevation.

45 Referring to the figures by characters of reference 1 designates an arcuate metal base bowed transversely and provided, at its ends, with tongues 2 for the reception of screws or other suitable fastening means indicated at

50 3. The pad or cushion to be used in connection with this strip 1 is made up of an elongated strip of leather 4 secured within a housing 5 of suitable fabric, there being a padding arranged along one side of this

strip and which is also housed within a fabric 55 3, the padding being indicated at 7.

An outer covering preferably of leather and which has been indicated at 8, is stretched over the fabric 5 and the padding therein and has its longitudinal end edges 60 inturned and sewed together, as indicated at 9. Thus it is possible by stitching these edges, to draw the leather tight over the parts inclosed thereby.

This strip 1 is adapted to rest in the recessed upper face of the crutch top A and the tongues 2 are adapted to lap and be secured to the ends of the crutch top.

It is to be understood that other means may be provided than those illustrated for 70 attaching the arm rest to the crutch top.

Obviously by providing an arm rest such as described, the parts can be assembled readily and held together efficiently. The only fastening means, in the forms shown, 75 are located at the ends of the crutch top. The sides of the rest will be substantially flush with the sides of said top and the entire structure will present a neat and attractive appearance.

80 The strip 1 is preferably made of resilient metal and as shown particularly in Figs. 1 and 2 has its intermediate portion spaced from the crutch top. The covering 8 extends between this resilient strip and the 85 crutch top and rests on said top. When considerable pressure is exerted downwardly against the arm rest the strip 1 will expand slightly so as to have a slight movement toward the crutch top, giving a spring cushioning effect.

90 What is claimed is:

1. An arm rest for crutch tops comprising a longitudinally bowed transversely arched strip, a flexible strip, a pad upon the flexible strip and secured thereto, a covering extending around the pad and flexible strip and means for securing the edges of the covering together under the bowed strip and throughout the length of the covering, said connected edges of the covering being normally spaced from the bowed strip.

100 2. An arm rest for crutch tops and the like, including a transversely arched resilient strip having its lower surface concaved from side to side, a cushion extending therealong, a flexible covering extending around the cushion and having its edges extended

across the concaved face of the arched strip and spaced from said face, and means for fastening said edges together.

3. The combination with a crutch top, of 5 a transversely arched resilient strip mounted on said crutch top and having its lower face concaved transversely and spaced therefrom, a cushion extending along said strip, a flexible covering housing the cushion and having 10 its edges inturned between the crutch top and the concaved face of the arched strip, and means for fastening said edges together to constitute a yieldable support for engaging the crutch top.

- 15 4. The combination with a crutch top, of an arm rest secured thereon and including

a resilient strip mounted for limited spreading movement, a pad on said strip, a flexible covering extending over the pad and having its edges inturned between said strip and the 20 crutch top, and means for fastening said edges together to hold them normally spaced from the resilient strip, said edges being supported by the crutch top.

In testimony that I claim the foregoing 25 as my own, I have hereto affixed my signature in the presence of two witnesses.

BENJAMIN FRANKLIN PEASE.
